UNITED STATES PATENT OFFICE.

GUY CARPENTER, OF NEW YORK, N. Y.

SPARK ARRESTER.

Application filed February 16, 1924. Serial No. 693,186.

My invention relates to the art of cooling and arresting heated substances which are produced by combustion in the fire-box of a locomotive engine and usually discharged through the smoke-stack.

The object of my invention is to cause the sparks leaving the fire-box to be carried through a long circuitous path in which they will be subjected to an extremely strong centrifugal force before they reach the smoke-box which, in itself, will have the result of cooling the substances.

Another object is to produce a device of this character which, by reason of its particular construction, will obviate the necessity of the utilization of a screen which I customarily use in devices for arresting sparks.

A further object is to provide, in combination with such a construction, a collecting chamber in which the substances, thus cooled, may be collected.

My invention may be more easily understood by reference to the accompanying drawings which embody a preferred form of construction. In the drawings, Fig. 1 shows a vertical longitudinal sectional view of a portion of the fire-box, smoke-stack, the chamber surrounding it, the smoke-box, and my improved construction which is, in this illustration, enclosed within the smoke-box;

Fig. 2 is a cross-section taken on the line 2—2 in Fig. 1.

Referring to the accompanying drawings, the reference numeral 10 is used to indicate the smoke-box of a locomotive and which, preferably, extends further forward than ordinary smoke-boxes now in use. The smoke-box for my purposes, may be constructed and attached to the present type locomotives as an extension, secured thereto in any suitable manner, and arranged at the front end to receive the front end connections of the locomotive. The numeral 11 indicates a cylinder smaller than the smoke-box and preferably mounted therein in such a manner as to provide an annular space, either concentric or eccentric, (as illustrated it is eccentric) between the outer surface of the cylinder and the inner surface of the smoke-box. The rear end of the cylinder 11 is in close proximity to the stack chamber and is completely closed therefrom by the division plate 12, which is perforated centrally to receive an open end of the central cylinder 13, mounted therein and is also provided with an opening

25 which connects the passage from the fire-box with the cylinder 11. The front end of this cylinder 13 is also open and the cylinder does not project forwardly as far as the end 60 of the smoke-box.

A helically formed member 14 surrounds, and is secured to, the inner cylinder 13, its outer end contacting the inner wall of the cylinder 11, its front end being open so as to communicate with a chamber 15, formed in the smoke-box in advance of the cylinder 13. 65

The inner surface of the cylinder 11 is provided, at selected points, with baffles 16 which are positioned to oppose the direction of the flow of gases, the purpose of these baffles being to catch any solid particles revolving around the inner surface of the cylinder 11. Slots, or orifices 17, extend through the cylinder 11, the baffles paralleling the said slots, the purpose of the slots being to permit the solids striking the baffles to pass through the cylinder into the space between the cylinder and the smoke-box. 70 75

As illustrated, the blades of the helically formed member 14 are inclined rearwardly, but it must be understood that they may be positioned at any angle and will function satisfactorily nevertheless. 80

The numeral 18 indicates the stack and 19 the stack-chamber, which has its base above the plane of the base of the cylinder 11 and an exhaust jet 20 extends from the bottom of the smoke-box upwardly through the base of the stack-chamber, said jet being obviously positioned centrally below the open bottom of the stack 18. By this construction, as illustrated, a chamber is formed which leads from the fire tubes 21, below stack-chamber 19 and opens into the lower portion of the cylinder 11, in which the cylinder 13 and the helically formed member 14 are located. Through the chamber thus formed, the gases from the fire tubes flow into the cylinder 11 and are then forced into a rotary motion, in passing around the cylinder 13 by striking the helically formed member, and finally they are discharged from the helically formed member into the chamber 15 at the forward part of the smoke-box and sucked back through the inner cylinder 13 to the stack-chamber and finally discharged through the stack.

As the velocities produced by the action of the jet 20 are very high, the gases in passing through the helically formed member are revolving at extremely high velocity, thus

creating a strong centrifugal force which acts upon the particles of solids, such as cinders, sparks and the like, in the products of combustion, and they are, consequently, thrown 5 outward against the inner surface of the cylinder 11, caught by the baffles 16 and conducted through the openings 17 into the annular space 22 between the cylinder 11 and inner surface of the smoke-box 10 and fall 10 to the bottom thereof. In the base of the smoke-box 10 I have provided a door 23, through which the solids dropping into this chamber 22 may be cleared out.

It is the utilization of the centrifugal action 15 for this purpose (and which is assured by my construction) which constitutes one of the principal objects of my invention. The centrifugal action thus created is capable of attaining great proportions, which tends to 20 make sure of the separation of the solids from the gases and has, furthermore, the advantage of not causing any reversal of flow which would seriously impede the draft and cause a loss thereof.

25 Another great advantage of my construction is that the products of combustion, after leaving the helically formed member 14 and before entering the cylinder 13, continue to revolve inside of the chamber 15 at a very 30 high velocity, thus still tending to retain any solid matter remaining in the products of combustion at the inner periphery of the chamber 15. This construction makes it very 35 difficult for these particles of matter to stop revolving and then reverse their direction of flow in order to enter cylinder 13, the result being that any particles which actually leave

the helically formed member will be caught in the chamber 15, from which they may be cleared out through the door 23.

Having thus described my invention, what I claim and desire to secure by Letters Patent of the United States is:

1. A spark arrester for locomotives employing a fire box, comprising a smoke stack; a smoke chamber; a cylinder, provided with longitudinal openings, mounted horizontally in the smoke chamber and in advance of the smoke stack; a baffle on the inner wall of said cylinder, adjacent each of said longitudinal openings; an inner cylinder, centrally located within the first mentioned cylinder; a helically formed member between the two aforesaid cylinders, to form a spiral passage; and means to conduct the smoke from the fire box to the spiral passage formed between said two cylinders, before the smoke is permitted to reach the smoke stack, substantially as shown and described.

2. A spark arrester for locomotives employing a fire box, comprising a smoke stack; a smoke chamber; a cylinder, provided with openings through its wall, mounted in the smoke chamber; a helically formed member, secured horizontally in said cylinder, and forming a spiral passage therethrough; a baffle on the inner wall of said cylinder, adjacent each of said openings; and means to conduct the smoke from the fire box to the spiral passage formed in said cylinder, before said smoke is permitted to reach the smoke stack, substantially as shown and described.

GUY CARPENTER.
